UNITED STATES PATENT OFFICE.

FREDERICK J. CLARK, OF BUFFALO, NEW YORK, ASSIGNOR TO EASTMAN MACHINE CO., OF BUFFALO, NEW YORK.

SHARPENING DEVICE FOR CLOTH-CUTTING MACHINES.

1,368,321.

Specification of Letters Patent. Patented Feb. 15, 1921.

Application filed December 16, 1918. Serial No. 266,888.

To all whom it may concern:

Be it known that I, FREDERICK J. CLARK, a citizen of the United States, residing at Buffalo, in the county of Erie and State of New York, have invented a new and useful Improvement in Sharpening Devices for Cloth-Cutting Machines, of which the following is a specification.

This invention relates more particularly to sharpening devices for the knives of cloth cutting machines of that type which are adapted to be moved about by hand on the cutting table to cause the knife to follow a pattern on the lay of cloth or material being cut.

These machines are commonly equipped with a sharpening device consisting of a pair of rotary emery or grinding wheels which are adapted to be pressed against the opposite sides of the edge of the knife and are driven by engagement with the rotating knife, thereby grinding or sharpening the edge. The sharpener has to be adjusted to different operative positions from time to time as the knife wears and decreases in diameter, and in the sharpeners as heretofore constructed, much difficulty has been experienced in getting the unskilled users of the machines to adjust the sharpener to the position relative to the knife required to insure proper sharpening of the edge. If the grinding wheels are adjusted outwardly too far in front of the edge of the knife, they are apt to turn over the edge or make the bevel too abrupt, whereas if the wheels are adjusted inwardly beyond the proper point they will form a thin feather edge which will readily nick or break off.

One object of the invention is to provide an efficient sharpener of simple and inexpensive construction having means which enables the operator to quickly and easily adjust the sharpener to proper sharpening relation to the knife and avoid the above mentioned difficulties heretofore experienced, simply by seeing that an indicator bears a prescribed relation to the edge of the knife.

Another object is to improve the sharpeners of cloth cutting machines in the other respects hereinafter described and set forth in the claims.

In the accompanying drawings:

Figure 1 is a side elevation of an electric cloth cutting machine provided with knife-sharpening means embodying the invention.

Fig. 2 is a similar elevation enlarged, of the sharpener.

Fig. 3 is a front elevation of the sharpener showing it in operative position relative to the knife.

Fig. 4 is a similar view showing the inoperative position of the sharpener.

Fig. 5 is a plan view, partly in section, of the adjustable support for the sharpener.

Fig. 6 is a fragmentary elevation showing the catch for holding the sharpener in the inoperative position.

The cloth cutting machine comprises, as usual, a flat base A adapted to rest and move upon the cutting table or other suitable supporting surface, beneath a lay of material to be cut; a thin upright standard B rising from the base; a circular knife C suitably journaled on the standard; and an electric or other suitable motor D supported by the standard and connected by suitable gearing or drive mechanism (not shown) with the knife for rotating the latter. Only enough of the machine is illustrated in the drawings to give a correct understanding of the construction and operation of the knife sharpener.

E E' represent two emery or grinding wheels which are suitably journaled on bearing arms or members 10 and 11 adapted to move toward and from each other to place the two wheels into and out of grinding contact with the opposite faces of the edge of the knife. The grinding wheels are disposed relatively to each other and to the plane of the knife in a well known manner, such that the wheels will be rotated by contact with the driven knife and will perform their function to the best advantage.

In the construction shown the bearing arms 10 and 11 are pivoted on fixed studs or journals 12 projecting from opposite sides of a support 13 which is adjustably mounted on the standard B, or other suitable part of the machine, so that the support can be adjusted to advance or retract the sharpener as may be necessary to cause the grinding wheels to contact with the knife nearer to or farther from the extreme edge. Each of the arms 10 and 11 is preferably adjustably secured by a split hub 14 and a clamping screw 15 to a sleeve 16 which is arranged to oscillate on one of the journals 12, and the two sleeves 16 are provided with intermeshing gear teeth 17 whereby the two bearing

arms are caused to swing simultaneously toward and from each other when the bearing arm for one of the wheels is moved. The arm 11 is provided with an extension 5 forming a handle for swinging the wheels into and out of contact with the knife. The adjustable connections between the wheel bearing arms and their bearing sleeves enable the arms to be set on the sleeves so that 10 the two wheels can be caused to simultaneously engage and bear with the required pressure against the opposite faces of the knife edge.

Preferably, the adjustable support 13 for 15 the sharpener is suitably pivoted at 18 on one side of the machine standard B and extends forwardly therefrom against the face of the standard, and is provided with a laterally projecting front end or portion on 20 which the bearing arms for the grinding wheels are mounted. The support is provided at its forward portion with a slot 19, curved concentrically with the pivot 18, through which passes a clamping screw 20 25 fixed to the side of the machine standard or frame. On this clamping screw or stud 20 is a thumb nut 21 by which the support 13 is adapted to be clamped stationarily in adjusted positions. 22 indicates an adjusting 30 screw which is suitably swiveled in the support 13 and turns in a threaded hole in a nut or member 23 which surrounds the clamping screw 20 between the thumb nut 21 and the support 13. By turning the adjusting screw 22, after first releasing the thumb nut 21, the support 13 can be moved to adjust the grinding wheels substantially in the direction of the plane of the knife toward and from the knife edge. This adjustment of the sharpener permits the 40 grinding wheels to be set in the proper positions at opposite sides of the edge of the knife irrespective of the decreasing diameter of the knife, due to wear. In the adjustment of the support 13 the grinding 45 wheels move in an arc which passes substantially through the axis of the knife, and the wheels therefore occupy substantially like, angular relations to the knife in the various 50 adjustments of the support. The support 13 pivoted and secured in the manner described, while enabling the ready adjustment of the sharpener, provides a very simple, strong and rigid support therefor, 55 which is not liable to work loose or get out of order and interfere with the proper action of the sharpener. The adjusting and clamping devices for the support 13 can be of other suitable construction.

60 24 indicates a pointer or indicator which is secured to or formed with the adjustable support 13 for the sharpener. The pointer is preferably secured to the support by screws 25 passing through slots in the shank 65 of the pointer, so that the pointer can be

properly adjusted when applying the sharpener to a machine. The pointer or indicator extends from the support toward the knife and in the adjustment of the support 13 moves in a plane substantially parallel with 70 and close to the plane of the rotary knife. The pointer or indicator is so positioned relatively to the grinding wheels and the cutter knife that when the end of the pointer is substantially opposite to the periphery of 75 the knife, as shown in Fig. 2, the grinding wheels will be in correct grinding relation to the knife. The pointer can be readily seen from the side of the machine and in order for the operator to correctly adjust 80 the sharpener for sharpening the knife, it is only necessary to adjust the sharpener by means of the adjusting screw 22 until the end of the pointer is directly opposite to the circle of the edge of the knife. The operator 85 is thus enabled to accurately position the sharpener without relying on his own judgment or opinion as to the correct position of the grinding wheels and the sharpener can be quickly and accurately adjusted by the 90 unskilled operatives who ordinarily use these cloth cutting machines, merely by following the simple direction to turn the screw 22 until the end of the pointer is opposite 95 the edge of the knife. When thus adjusted the knife is sharpened by pressing the grinding wheels against the knife by means of the handle on the bearing arm 11. After using the sharpener, the grinding wheels are 100 swung up to the position shown in Fig. 4 where they are releasably retained out of the way by the engagement of the screw 15 on the bearing arm 11 with a spring catch or holding device 26 on the support 13.

I claim as my invention:

1. In a cloth cutting machine, the combination with a driven knife, and a sharpening member arranged to contact with the knife for sharpening it, of means for adjusting said sharpening member relative to the knife so that the sharpening member will occupy like relations to the edge of the knife as the width of the knife is lessened by wear, and an indicator which has a fixed relation to the sharpening member and partakes in the adjustment of the sharpening member and indicates when in a prescribed position relative to the knife the correct operative adjustment of the sharpening member.

2. In a cloth cutting machine, the combination with a driven knife, and a sharpening member arranged to contact with the knife for sharpening it, of means for adjusting said sharpening member relative to the knife so that the sharpening member will 115 occupy like relations to the edge of the knife as the width of the knife is lessened by wear, and a pointer which is adjusted with the sharpening member toward and from the edge of the knife by the operation of said 120 125 130

adjusting means and indicates the correct operative adjustment of the sharpening member when the end of the pointer is substantially opposite the cutting edge of the 5 knife.

3. In a cloth cutting machine, the combination with a driven knife, and a knife sharpening member, of a support on which said sharpening member is mounted to move 10 into and out of sharpening contact with the knife, means for adjusting said support to place the sharpening member in correct sharpening relation to the knife so that the sharpening member will occupy like relations to the edge of the knife as the width 15 of the knife is lessened by wear, and an indicator which is connected to said support and indicates when in a prescribed position relative to the knife the correct adjustment 20 of the sharpening member.

4. In a cloth cutting machine, the combi-

nation with a driven knife, and a pair of grinding wheels, of a support on which said wheels are mounted to move toward and from the plane of the knife into and out of 25 contact with the opposite sides of the knife edge, means for adjusting said support in the direction of the width of the knife, so that the grinding wheels will occupy like 30 relations to the edge of the knife as the width of the knife is lessened by wear, and an indicator which is connected to said support and indicates when in a prescribed position relative to the knife the correct adjustment of said wheels. 35

Witness my hand this 12th day of December, 1918.

FREDERICK J. CLARK.
